UNITED STATES PATENT OFFICE.

CHARLES M. WEEKS AND DAVID BLOCH, OF WALDEN, NEW YORK, ASSIGNEES TO CHARLES M. WEEKS COMPANY, INC., OF WALDEN, NEW YORK, A CORPORATION OF NEW YORK.

PENCIL-PRINTING MACHINE.

Application filed May 26, 1922. Serial No. 563,802.

To all whom it may concern:

Be it known that we, CHARLES M. WEEKS and DAVID BLOCH, citizens of the United States, residing at 93 Ulster Avenue, 5 Walden, N. Y., and 11 Gladstone Avenue, Walden, N. Y., respectively, have invented certain new and useful Improvements in Pencil-Printing Machines, of which the following is a clear, full, and exact description.

12 This invention relates to machines for printing or stamping names, words or insignia upon pencils or similar articles.

One object of the present invention is to produce a machine upon which any desired name or word may quickly and easily be printed upon a pencil or similar article.

Another object of the invention is to produce a coin-controlled machine of this class upon which a name, word or symbol may readily be printed or stamped on a pencil or like article.

Another object of the invention is to devise a pencil printing machine in which only pencils especially constructed to pass through the machine may be placed in the machine and printed.

A still further object of the invention is to produce a machine of the class described in which pencils may be taken in succession from a magazine, printed or stamped with a word, name or symbol and then discharged in succession from the machine.

With these objects in view, the invention comprises certain novel and improved features, constructions and combinations of parts hereinafter described and particularly pointed out in the claims, the advantages of which will be readily understood and appreciated by those skilled in the art.

40 The invention will be clearly understood from the accompanying drawings illustrating a machine embodying the invention in its preferred form and the following detailed description of the construction therein shown.

In the drawings—

Figure 1 is a perspective view illustrating a machine embodying the invention;

Fig. 2 is a view in front elevation of the machine, with a portion of the casing re-

5 moved to show the structure within the same;

Fig. 3 is a plan view of a portion of the machine with part of the casing removed;

Fig. 4 is a central vertical sectional view 55 of the machine;

Fig. 5 is a view similar to Fig. 4 illustrating certain of the parts in different positions;

Fig. 6 is a detail view illustrating particularly stopping devices for certain of the operating parts;

Figs. 7 and 8 are detail sectional views illustrating the operation of certain parts of the pencil handling mechanism; and

Fig. 9 is a view illustrating a pencil after 65 it is printed on the machine.

The machine embodying the invention in its preferred form, as illustrated in the drawing, comprises a printing mechanism 70 which may be adjusted to print any desired name or word upon a pencil presented thereto.

The printing mechanism comprises a series of printing disks indicated at 2 rotatably mounted side by side upon a shaft 4 75 supported at its ends in the casing 6, these disks being provided on their peripheral edges with a series of letter type, indicated at 8, from A to Z. These disks may, of course, be also provided with number type 80

or with various printing insignia, if desired. Each of these disks is arranged for adjustment about the shaft 4 to bring any letter thereon into a position to print a pencil 85 presented in printing position. To this end, each disk carries an arm 10 secured thereto and projecting upwardly from the disk through a slot between bars 12 secured to the casing 6. Each of the bars 12 carries

a series of letters which are the same as the 90 letters on the corresponding disk 2. To locate any desired one of the letter type on one of the disks 2 in printing position, the arm 10 on the disk is adjusted so that it is

95 opposite the same letter on the bar 12 corresponding to said disk. To assist in locating the disks accurately, and to secure the disks in adjusted position, each arm 10 is

provided with a laterally extending flange 14 arranged to engage in any one of a series 100

of notches 16 formed in each of the bars 12 respectively opposite each letter on said bar.

The pencil holding and handling mechanism in the present machine comprises a magazine adapted to hold a series of pencils, and mechanism for taking the pencils in succession from the magazine and presenting the same to the printing disks. The magazine for the pencils of the present machine is formed by two channel bars 18 and 20 extending in a vertical direction and adapted to receive the opposite ends of a pencil, as shown in Fig. 3. In order that only specially constructed pencils may be introduced into the magazine, the channel bar 18 is constructed considerably narrower than the full diameter of a pencil. With this construction of the channel bar 18, one end of the pencil must be reduced in diameter, as shown at 22, Fig. 9, in order that the pencil may fit accurately in this channel bar. Figs. 4 and 5 show the magazine loaded with a series of pencils.

The pencils drop from the lower end of the magazine successively upon a pair of supporting plates 24 secured to the underside of a transversely movable pencil supporting and actuating slide 26. A pencil when resting on said plates 24 is located in front of the edge of the slide 26, as shown in Fig. 4, and the channel bars 18 and 20 terminate just above the slide to allow transverse movement of the slide and pencil carried thereby. Fig. 4 shows the position of the parts when the machine is at rest or out of operation. In presenting a pencil to the printing disks, the slide 26 is moved forwardly transversely of the magazine from the position shown in Fig. 4 to the position shown in Fig. 5, thereby carrying the lowermost pencil supported on the plates 24 into contact with the edges of the printing disks, which print the desired name, word or insignia thereon. The slide 26 is then retracted to its initial position. As the slide 26 advances it closes the lower ends of the channel bars 18 and 20, thereby preventing the pencils from dropping from the magazine.

During the retracting movement of the slide 26, the pencil is thrown off the plates 24 by means of two pivoted fingers 28 arranged to engage the opposite ends of the pencil. These fingers are each pivoted at 30 upon a bracket 32 in position to be engaged by the pencil carried by the slide 26 as the slide is moved forwardly, the fingers then swinging forwardly as shown in Fig. 7, and dropping down behind the pencil after the pencil has passed the same. During the retracting movement of the slide 26, the pencil is again engaged by the fingers 28, but the fingers are then prevented from swinging rearwardly by their engagement with the bracket 32, as shown in Fig. 8, so that the pencil is thrown off the plates 24 by the

fingers as the slide 26 continues its retracting movement. The pencil then drops down upon an inclined chute 34, preferably constructed of sheet metal, and is discharged from the chute through an opening 36 in its casing. As the slide is restored to its original position, the next pencil drops from the magazine onto the plates 24.

The slide 26 is arranged to be actuated in the manner described by mechanism preferably arranged to be controlled manually from the outside of the casing. The slide is actuated from a pair of rotatable disks 38 fixed to a shaft 40 mounted to rotate in suitable bearings secured to the side walls of the casing 6, the disks being connected with the slide by means of links 42. The shaft 40 is adapted to be rotated in a clockwise direction (Figs. 4 and 5) to advance the slide 26 by means of a crank arm 44 secured to the shaft outside of the casing and preferably provided with a suitable handle. The shaft 40 is rotated in the opposite direction to restore the parts to their normal positions by means of a coiled spring 46 attached at one end to an arm 48 secured to the shaft 40, and at its other end to the base of the casing. The movement of the shaft and disk 38 under the influence of the spring 46 is limited by means of a stop 50 secured to one of the disks 38 which is arranged to engage a stop 52 secured to the side wall of the casing (see Fig. 6).

The crank arm 44 is preferably actuated so as not only to bring a pencil carried by the slide 26 into contact with the type on the peripheries of the printing disks, but also to press the pencil with considerable pressure against the type. The pressure of the pencil on the type causes the type which projects outwardly from the printing disks to break the hard-finished surface on the pencil, so that the ink will be deposited in the depressions and will adhere to the pencil. The slide 26 serves as an abutment or anvil 110 against which the pencil rests during the compressing operation.

As the shaft 40 and disk 38 are rotated to advance the slide 26, an inking mechanism is actuated to apply ink to the type 11 on the disks 2 with which the pencil is to be brought in contact. This inking mechanism comprises an inking roller 54 rotatably mounted in the upper ends of two arms 56 pivoted at 58 on the respective disks 38, the roller being provided with any suitable covering adapted to be saturated with ink. The arms 56 are each acted upon by a coiled spring 60 which tends to swing the inking roller 54 forwardly toward the printing disks. In order to guide the inking roller in its movement so that it will ink the line of type with which the pencil is to be brought in contact but will not deposit ink on any considerable portions of 130

is not limited to the particular construction and arrangement of parts of the illustrated embodiment thereof, that the invention may be embodied in other forms within the scope 5 of the claims.

Having explained the nature and object of the invention and having specifically described a construction embodying the invention in its preferred form, what is claimed 10 is:

1. A pencil printing machine having, in combination, a pencil magazine comprising channel bars arranged to receive the ends of a pencil and constructed so that an ordinary pencil may not be inserted therein, a slide arranged to move transversely of the magazine, pencil-supporting plates carried by the forward end of the slide upon which the pencils drop in succession from the magazine, a printing mechanism located at one side of the magazine and comprising a series of rotatable disks arranged side by side and having type upon their peripheries, arms secured to said disks, indicator bars between 15 which said arms extend, letters or other insignia on said bars corresponding to the type upon the peripheries of the respective disks, a rotatable shaft, a hand-lever secured to said shaft, connections between the shaft and the slide for advancing the slide to carry a pencil into contact with said disks and to retract the slide, and coin-controlled means for locking the shaft and said slide from movement.

2. A pencil printing machine, having in combination adjustable printing mechanism, a magazine adapted to hold pencils side by side, a transversely movable carrier arranged to receive a pencil from the magazine and to carry a pencil, by its transverse movement, into printing contact with the printing mechanism, a movable inking device for inking the type along the printing line, a lever and connections between the lever and the carrier and between the lever and the inking device for actuating the carrier and the inking device.

3. A pencil printing machine having in combination an adjustable printing mechanism, a magazine adapted to hold pencils side by side, a transversely movable carrier arranged to receive pencils from the magazine and to carry pencils by its transverse movement into printing contact with the printing mechanism, means for actuating the carrier manually and coin-controlled mechanism for locking and releasing said means.

4. A pencil printing machine having in combination an adjustable printing mechanism, a magazine adapted to hold pencils side by side, a transversely moving carrier arranged to receive pencils from the magazine and to carry pencils by its transverse movement into printing contact with the

printing mechanism, a movable inking device for inking the type along the printing line, a lever and connections between the lever and the carrier and between the lever and the inking device for actuating the carrier and the inking device, and coin-controlled means for locking and releasing the lever.

5. A pencil printing machine having in combination a pencil magazine arranged to hold pencils side by side, a slide mounted for movement transversely on the magazine, pencil supporting plates carried by the forward end of the slide upon which the pencils drop in succession from the magazine, a printing mechanism located at one side of the magazine and comprising a series of rotatable discs arranged side by side and having type upon their peripheries, arms secured to said discs, indicator bars between 80 which said arms extend, letters or other insignia on said bars corresponding to the type upon the peripheries of the respective discs, a rotatable shaft, a hand-lever secured to said shaft, connections between the shaft and the slide for advancing the slide to carry a pencil into contact with said discs and to retract the slide, and coin-controlled means for locking the shaft and said slide from movement.

6. A pencil printing machine having in combination adjustable printing mechanism, a magazine adapted to hold pencils side by side, a transversely movable carrier arranged to receive pencils from the magazine and to carry a pencil by its transverse movement into printing contact with the printing mechanism, a rock shaft, connections between the shaft and the carrier for actuating the carrier, an inking roller, connections between the shaft and the roller for rolling the roller over the printing line, and manually operable means for actuating the shaft.

7. A pencil printing machine, having in combination a pencil magazine arranged to hold pencils side by side, printing mechanism, means for taking pencils from the magazine and bringing them into printing contact with the printing mechanism, a rotatable shaft, means secured to the shaft and projecting therefrom, inking roller supporting means pivoted to said first means, an inking roller carried by said supporting means, yielding means acting on said supporting means for holding the printing roller in position to engage the type, supporting means, guiding means for the roller to cause it to engage only the printing line of the printing mechanism, and means for turning the shaft.

8. A pencil printing machine, having in combination a magazine arranged to hold pencils side by side, a transversely movable slide, an adjustable printing mechanism on

the peripheries of the type disks upon teeth 68, thereby unlocking the disks 38 and the shaft 40. The rear arm of the lever 64, as it is elevated, engages the forward end of a curved stop lever 76, thereby limiting the movement of the lever 64, and 70 the coin still remains engaged in the passage in the coin guide 70 and rests on the forward end of the lever 64 until the shaft 40 and disks 38 are actuated to advance the slide 26. The stop lever 76 is pivoted at 75 78 on the casing and is arranged to engage the edge of the adjacent disk 38, as shown in Fig. 4, the lever being held yieldingly in contact with the periphery of the disk by a coiled spring 80. As the shaft 4 and 80 disks 38 are turned in a clockwise direction, a projection 82 on the contacting disk 38 engages the lever 76 and swings the same rearwardly, thereby releasing the locking lever 64 and allowing the lever to swing 85 far enough under the weight of the coin to release the coin from the passage in the coin guide 70. The coin then drops downwardly into a suitable receptacle releasing the lever 64, and the lever 64 swings back 90 into engagement with the periphery of the adjacent disk 38 so that its rear end will engage in front of the tooth 68 as said disk is restored to its original position.

In the present form of the invention, the disks 38 and shaft 40 are normally locked 95 in position so that they cannot be rotated to advance the slide 26 to bring a pencil in contact with the printing mechanism. The locking mechanism for these parts is coin-controlled and is actuated to release the disks and shaft upon the insertion of a suitable coin in the machine. The locking mechanism comprises a locking lever 64 pivoted at 66 on one of the side walls of the casing, the rear end of which is arranged 100 to engage a tooth 68 on the adjacent disk 38 to lock the disks and shaft 40 from rotary movement in a clockwise direction. The lever 64 is mounted on its pivot or is weighted so that the rear arm thereof is slightly heavier than its forward arm and will normally be held by gravity in depressed or locking position in front of the tooth 68. The forward arm of the lever 64 is arranged to extend beneath a passage 105 in a coin guide 70 secured to the casing 6 and arranged to receive coins from a passage in a coin-receiving device 72 secured to the upper part of the casing. The coin-receiving device 72 is provided with an opening 74 (see Fig. 2) in which coins may be placed to insert the same in the machine. When a coin of the proper size has been placed in the coin-receiving device 72, it drops down through 110 the passage therein and through the passage in the coin guide 70 until it engages the forward arm of the lever 64. The weight of the coin depresses the forward arm of the lever 64 and lifts the rear arm 115 of the lever out of position to engage the

In operating the above described machine, the arms 10 on the printing disks are adjusted respectively opposite the letters on the bars 12 corresponding to the name or word which is to be printed on a pencil, the engagement of the flanges 14 on the levers in 100 the notches 16 in the bars bringing the desired letters to the proper alignment in printing position. Either before or after the printing disks are adjusted a coin of the proper denomination is placed in the opening 105 74 in the coin receiver. This unlocks the pencil actuating mechanism. The operator then grasps the handle of the arm 44, swings the arm forwardly and then allows the same to swing back under the influence of the 110 spring 46. This operation brings the pencil into contact with the line of type on the printing disks and then releases the pencil so that the pencil drops down on the inclined chute 34 and is discharged from the 115 casing through the opening 36.

Pencils having names printed thereon have recently been produced and sold commercially to a considerable extent. As far as applicant is aware, however, such pencils have 120 been produced only on special order from the manufacturer. The above machine enables anyone to secure at comparatively small expense a pencil with his name printed in an attractive manner thereon. The machine is 125 comparatively simple in construction, inexpensive to manufacture, and pencils may be quickly and easily printed thereon without the exercise of any particular skill.

It is to be understood that the invention 130

one side of said magazine, a rock shaft, mechanism for moving the slide from the shaft, a member projecting from said shaft, a lever pivoted on said member, an inking roller carried by said lever, a spring acting on said lever for holding the printing roller in position to engage the type, guiding means for the printing roller to cause it to engage only the printing line and means for turning the shaft.

9. A pencil printing machine having in combination an adjustable type mechanism, a magazine adapted to hold a plurality of pencils, a member adjacent to the magazine arranged to receive the pencils in succession therefrom, means for moving relatively said pencil and type mechanism into printing contact while the pencil is supported by said receiving member, and coin-controlled mechanism for operating said means.

10. A pencil printing machine having in combination an adjustable type mechanism, a magazine adapted to hold a plurality of pencils, a printing anvil adjacent to the magazine arranged to receive the pencils in succession therefrom, and coin-controlled means for compressing a portion of the pencil between the type and the anvil.

11. A pencil printing machine having in

combination an adjustable printing disk rotatably mounted, a series of type mounted upon the periphery of said disk, an inking device for said type, a magazine adapted to hold a plurality of pencils, a printing anvil adjacent to the magazine and arranged to receive the pencils in succession therefrom, and coin-controlled means for compressing a portion of a pencil between the type and the anvil.

12. A pencil printing machine having in combination an adjustable printing disk rotatably mounted, a series of type mounted upon the periphery of said disk, a magazine adapted to hold a plurality of pencils, a printing anvil adapted to receive the pencils in succession from said magazine, means for preventing the passage of standard pencils through the magazine to the anvil, and coin-controlled means for compressing a portion of a pencil between the type and the anvil.

Signed at Walden, N. Y., this 24 day of May, 1922.
